CLAIM

The ornamental travel razor set, as shown and described.

DESCRIPTION

FIG. 1 is a perspective view of a travel razor set, showing our new design;

FIG. 2 is a side elevational view thereof, the opposite side being substantially a mirror image thereof;

FIG. 3 is a top plan view thereof; and,

FIG. 4 is a bottom perspective view thereof.

The broken line showing of a horizontal support bar in FIGS. 1 and 2 is for illustrative purposes only and forms no part of the claimed design.
